(57) **CLAIM**

I claim the ornamental design for a corner wheel of a suitcase, as shown and described.

DESCRIPTION

FIG. 1 is a right side perspective view of a corner wheel of a suitcase, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an environmental reduced scale front view of the wheel in FIG. 2, shown in an alternate position.

1 Claim, 5 Drawing Sheets
